UNITED STATES PATENT OFFICE.

EDWARD MATTOCKS, OF LYNDON, VERMONT.

SHUTTER-OPERATOR.

Specification of Letters Patent No. 27,458, dated March 13, 1860.

To all whom it may concern:

Be it known that I, EDWARD MATTOCKS, of Lyndon, in the county of Caledonia and State of Vermont, have invented a new and useful Improvement in Operating Window Blinds, Shutters, &c.; and I do hereby declare that the same is fully described and represented in the following specification and the accompanying drawings, of which—
10 Figure 1, denotes a front elevation of a window frame having a blind applied thereto and provided with my improvement. Fig. 2, is an inner side elevation of the window frame showing the head of the guiding tube. Fig. 3, is a side view of the guide tube to be hereinafter described.

The nature of my invention consists in applying to a window frame and blind, certain devices (as hereinafter set forth) for 20 controlling the movements of the said blind, whereby it may be unlatched, opened or closed, and relatched, without the necessity of raising the sash of the window.

In the drawings above mentioned, A, represents a window frame (provided with a sash) and having a blind, B, hinged or applied thereto in the ordinary manner. From the lower side of the said blind, a spring catch bar, D, is attached, the same having a 25 double catch, *a*, *a*, constructed and disposed upon its outer end in the usual way. Near the lower part of the window frame, A, and transversely thereof, a hole or passage, *c*, is formed, and within the same a cylindrical pipe is placed, and properly secured. Through this latter pipe, the longer arm, *d*, of a rectangular tube, C, is disposed, the 30 same being of such size as to be capable of being readily revolved, as well as slid longitudinally therein. On the inner end of said longer arm, *d*, a button or milled head, *e*, is secured, the same being for the purpose of actuating the said tube, C. The object 35 of this peculiar formation and arrangement of the tube, C, is to obtain a ready means whereby, by the use of a single tube and cord, the line of traction may be varied so that the blind may be either drawn toward the window, or pulled backward therefrom,

as circumstances may require. Through the 50 said tube a cord or rope, *f*, is carried and has one end attached at or near the outer part of the spring bar, D, or that which carries the double catch, the other end of such cord projecting from the button or head, *e*, as 55 seen in Fig. 2.

Having thus described the construction of my invention, I will now describe its operation.

If we suppose the blind to be closed, and 60 we desire to open the same and fasten it back or to the side of the building, to which it may be applied, we first grasp the button, *e*, on the inside of the window frame and push the tube outward; we next pull on the 65 cord sufficiently to slightly depress the spring catch bar, D, or enough to throw the catch out of engagement with its fastener; next we cause the tube to make one half of a revolution, or move through an arc of 70 ninety degrees, the shorter arm of the tube sweeping downward in the movement; next, pull upon the cord to cause the blind to swing around or into a proper position for being locked or fastened; next draw in the 75 tube and cord, and the operation is completed.

From the above it will be seen that the object aimed at, is accomplished in a simple, easy, and effective manner, and that 80 the mechanism employed is also very simple, and not liable to derangement.

What I claim is—

The combination of devices herein set forth, for controlling the movements of a 85 window blind, whereby it may be unlatched, opened or closed, and relatched, (as circumstances may require) such devices being the rectangular tube, C, the spring catch bar, D, and the cord, *f*, the same being arranged 90 and made to operate together, substantially in manner as set forth.

In testimony whereof I have hereunto set my signature this 25 day of July A. D. 1859.

EDWARD MATTOCKS.
